UNITED STATES PATENT OFFICE

FRANK J. SEMOTAN, OF TAMA, IOWA

FRUIT JAR

Application filed April 8, 1929. Serial No. 353,433.

This invention relates to jars used in the preservation of fruits, vegetables, fruit juices and the like.

The object of the invention is in the main to improve the closure of the jar, so that it may be hermetically sealed with comparative ease by woman or a child, and as easily unsealed.

A further object is to provide a closure which is at once a hermetical seal for the broad mouth of a jar and an extended bottle neck or nozzle convenient for the pouring out of a liquid, thus adapting the vessel for convenient filling with either fruit or fruit juice, and the equally convenient emptying of the same in either case.

The invention is fully disclosed in the description and claims following, reference being had to the accompanying drawing, in 20 which:—

Fig. 1 is a side elevation of a jar embodying my improvements. Fig. 2 is a central, vertical section of the upper portion of the same. Fig. 3 is a plan view of the closing 25 parts of the jar. Fig. 4 is a view from below of the bottle-mouth portion of the closure above the section line 4—4 of Fig. 2. Fig. 5 is a side elevation of the jar-closing head detached.

In the drawing the numeral 5 denotes a 30 fruit-jar, having a body of substantially a standard type. The neck 6, however, instead of being screw-threaded, has a terminal annular flange 7, giving the mouth of the jar a fairly wide and flat annular ring to form a 35 seat for a flat gasket 8. The neck is also shouldered at 9 to form a retaining rib for an encircling wire 10 connected by a twist at 11. The wire embraced a pair of upstanding bolts 12 provided with thumb-nuts 13, 40 for the clamping closure of the jar, as will presently appear.

A molded glass head 14 has an annular flange 15, flat, and matching the top of the 45 jar. The flange carries a ring-like yoke 16, having lateral lugs 17 pierced for the clamping bolts. Set in the position shown in Figs. 1 and 2 with the gasket in place between the jar and the head, the thumb-nuts are very 50 easily screwed down to make an air-tight

joint between the head and jar. So also, when it is desired to open the jar, the nuts are quite as easily unscrewed, when the head may be detached. The wringing action of the screw-top jar, which is apt to break the rubber gasket rings, and is always hard straining for a woman, is thus entirely avoided.

In practice it is preferred to form the head for double closure. It is accordingly provided with a conical body 18 terminating in a cylindrical bottle-mouth 19. An annular shoulder 20 is notched at 21 for clamp-bolts 12^a provided with thumb-nuts 13^a. The bolts are held in position by a wire ring 10^a, 60 similar to that already described. The bolts engage a top-plate 22 by its pierced lugs 23, and bind closely into the bottle-mouth a convex capping gasket 24. The jar may then be used as a bottle, by manipulating the outer 65 closure independently of that binding the head to the jar. For the pouring of liquids, such as fruit juices, this is more convenient than pouring from the large mouth of the jar.

Having thus described my invention, I claim:

1. In a fruit-jar and closure, the combination of a jar having an annularly expanded, flat-topped mouth, a wire-ring retaining shoulder formed on the neck, a pair of clamp-bolts with thumb-nuts held by an encircling wire under said shoulder, a head formed with a marginal, flat annular flange to match the mouth of the jar, and a ring-like yoke encircling the head and engaging said flange, with pierced lugs engaged by the clamp-bolts, whereby the head is drawn to a sealing position on an interposed gasket.

2. In a fruit-jar assembly, the combination of a jar having an expanded, flat-topped mouth, a neck provided with an outstanding, wire-ring retaining shoulder, clamp-bolts with thumb-nuts held in upstanding position by the wire ring, a head having a conical body with an outstanding annular flange fitting the mouth of the jar, a yoke encircling the head body and engaging said flange, a like arrangement of clamp-bolts, holding wire and 100

and wire-retaining shoulder on a reduced extension of the head, a cap-plate engaged by the last named clamp-bolts, and a convex gasket clamped in the bottle-mouth of the head.

5 In testimony whereof I affix my signature.

FRANK. J. SEMOTAN.
